UNITED STATES PATENT OFFICE.

ERNEST EDWARD RIGOLD, OF ASHFORD, ENGLAND.

DESIGN FOR A PLATE FOR A SOCK SUSPENDER.

Application filed July 11, 1928, Serial No. 27,445, and in Great Britain April 3, 1928. Term of patent 14 years.

To all whom it may concern:

Be it known that I, ERNEST EDWARD RIGOLD, a subject of the King of Great Britain, residing at Ashford, Kent, England, and having his post-office address at Rushbourne, High Halden, Ashford, Kent, England, have invented a new, original, and ornamental Design for a Plate for Sock Suspenders, of which the following is a specification, reference being had to the accompanying drawing.

Fig. 1 is a front elevation and

Fig. 2 is a plan view of a plate for a sock suspender showing my new design.

I claim:

The ornamental design for a plate for a sock suspender substantially as shown.

In testimony whereof I have signed my name to this specification.

ERNEST EDWARD RIGOLD.
